UNITED STATES PATENT OFFICE.

SAMUEL FREDERICK STEVENS, OF NORTH ADAMS, MASSACHUSETTS.

RAILWAY TIME-TABLE AND DISTANCE GUIDE-BOOK.

SPECIFICATION forming part of Letters Patent No. 310,330, dated January 6, 1885.

Application filed February 28, 1884. (Model.)

To all whom it may concern:

Be it known that I, SAMUEL FREDERICK STEVENS, of the town of North Adams, county of Berkshire, State of Massachusetts, have invented a new and useful Improvement in Railway Guide-Books, and of which the following is a specification.

My invention relates to the relative form given to the index fly-leaves of a guide-book, and in combination therewith upon the leaves of the latter the arrangement hereinafter described of the printed matter, stating the through distances between terminal railway stations, the local distances between stations, the time of the arrival and departure of trains, the stations where trains meet, the scheduled number of the trains, and the capacity of the side-tracks of each station, said guide-book being more particularly adapted for the use of conductors and train-men. As heretofore made this class of matter was compiled and printed on a large sheet, which had to be folded up to be carried in the pockets of those who used them, from which they soon became worn at their corners and easily torn, and being of a large size from necessity as the matter was arranged, they were badly adapted to be opened out for examination as the train on which they were used was moving, and when the wind was blowing it was very difficult to handle them.

To produce a guide-book in which all the matter before named can be seen at a glance, and which book can be carried in the pocket, is the object of my invention.

Accompanying this specification, and forming a part of it, there are two plates of drawings containing two figures illustrating my invention with the same designation of its printed matter by letter-reference used in both of them.

Of these illustrations, Figure 1 shows as printed on the first page where open the name of the terminal stations, the local distance between stations, and the side-track capacity of each station. This illustration shows also the manner of cutting the fly-indices of each page to show when printed thereon the names of the stations in their order and the scheduled number of the trains. This figure shows as

arranged on the inner face of the cover where open the special rules of the railway company. Figure 2 shows the book as opened at a page intermediate to the first and last pages, there being shown as printed upon the right-hand page facing the sight where opened the running time of one of the trains, whose scheduled number is printed upon the fly-index of that page, and upon the left-hand page, with the book so placed and opened, the running-time of the other train whose number is also on the same index-fly, the points where trains meet and pass being indicated by the heavier type used in designating such points.

For illustration I have shown my invention as applied in its arrangement of subject-matter to the uses of the Troy & Boston Railway, although by substituting the station-names of any other route and figures representing, relatively, in the same manner, the same matter as connected therewith it may be applied to the uses of any other railway.

In Fig. 1 there are three columns of figures arranged upon the page proper and one column of figures in line upon the fly-indices of all the pages in sight when the book is opened at the said first page. One of these columns, and that indicated at *a*, denotes the distances between the terminal station, as Troy, and each station. The column designated at *b* indicates the distances between stations, or "local distances," as they are termed. The column designated at *c* indicates the side-track car capacity of each station. The column of figures indicated on the fly-indices of the pages, and designated at *d*, denotes the scheduled number of the trains, there being also shown on the fly-index of each page the names of two of the road stations *e* in their order. The matter thus compiled and arranged on the first page is used in the following manner: To find the distance between the terminal station (herein designated as Troy) and any succeeding station on the road, refer to the figures in the column *a*, opposite the name of such succeeding station. Thus from Troy to North Adams it is 47.80 (forty-seven and eighty hundredths) miles. To find the distance between stations, refer to the figures in the column *b* which are opposite the

stations. Thus from Williamstown to Blackington the figures opposite the latter station indicate one and three-fourths mile. To find the side-track car capacity of a station, refer 5 to the column of figures indicated at *c*, and find the number in that column opposite such station. Thus the side-track capacity of Hoosic Junction is for two hundred cars.

Where branches connect with a main line 10 the distance-column commences from the station where connection is made with the main line, the local distances being continued in the same manner, and the side-track capacity continued under the trunk-line column expressing the same matter. Thus from Hoosic Junction, where the Troy & Beunington road connects with the Troy & Boston, to the next station of the branch (North Hoosic) it is one mile, and the side-track car capacity of 15 North Hoosic is seventeen cars. The fly-index of each page, excepting the first, is cut to underlap in its downward extension the fly of the page which numerically next precedes it, and to have printed on its downward subtending extension of the fly in their order the names of two stations more than are printed on said page which numerically next precedes it, so that each left-hand page of the book when 20 the latter is open shows, in connection with 30 the fly-indices of the succeeding pages, the names of all the stations in their order.

In Fig. 2 the guide-book is shown as opened at pages 3 and 4, where the compiled matter refers to the running-time of the trains scheduled as Nos. 3 and 4, and as the relative compilation of matter would be the same in all the pages excepting the first, a description of the arrangement of the matter shown at Fig. 2 will answer for that of all the intermediate 40 pages.

In Fig. 2 the column of figures indicated at *f* denotes the running-time of train No. 3, and the column of figures upon the right-hand page of the open book designated at *g* indicates the running-time of the train scheduled as No. 4. These trains run in opposite directions from each end of the road, the train-time indicated at *f* being that of the train leaving Troy, and to find when it will be at 45 any particular station on the road refer to the figures in the column *f* opposite the stations. Thus this train No. 3 will arrive at Eagle Bridge at 7:54 a. m., the latter figures being opposite said station in column *f*.

To determine the time at which train 4 will 55 reach any station, refer to the figures that are opposite such station in column *g*.

When other trains than those whose scheduled numbers are upon the index-fly of the 60 open page are running on the same track, such trains are designated by reference letters, numbers, or characters printed upon the left-hand page of the open book, as indicated at H. Opposite these numbers, letters, or 65 characters there is printed also what they are to indicate where applied to the time-columns

f and *g*. Thus the letter H is used to indicate, where applied to the time-columns, the time of meeting and the station where trains 70 3 and 4 meet. The letter E is used to indicate, when applied to the time-columns *f* and *g*, when and where trains 3 and 2 meet, the latter train being one whose scheduled number is not upon the fly of the page where open. The character + is used, as the printed 75 matter opposite to it states, upon the left-hand page to indicate, where applied to the time-columns, when and where train 4 passes train 2, and thus the movement of other trains on the road, whose numbers are not on the fly of 80 the open page, and their relative position may be indicated.

As thus compiled and arranged, a compact time-table and distance guide-book is produced which may be carried in the pockets of 85 those who use them, and in which, as the same is made up, it has the compiled matter in a form to be easily accessible.

Where long lines of road are being operated in divisions, the same system and arrangement of matter as applicable thereto may be used for each division as I have illustrated it applied to a short line of road. 90

When changes are made in the running-time of the trains, instead of being compelled 95 to print a new time-table, as has been the usual custom in such cases, gummed strips, having printed thereon the new time, may be pasted on over the columns indicating the former time of running the trains.

I make no claim in this application for a railway guide-book with index-leaves having thereon the names of two stations in their order and columns of figures opposite the names of the stations, separately indicating the distances between the upper stations of the fly-leaf where the book is opened and each succeeding station below, and columns of figures indicating the distance between intermediate stations, as the same forms the subject of another application for patent filed by me November 13, 1883, and still pending. 105

Having thus described my invention, what I claim, and desire to secure by Letters Patent, is—

1. The combination, in a railway guide-book, of an underlapping fly-index on each right-hand page, each of which indices, excepting the first, has printed thereon the names of two more stations in their order 110 than the next preceding page, as herein shown, columns of figures on the first right-hand page of the book, which, where opposite the station-names, separately indicate the distances between the first station and each succeeding station, the distances between each station and the one succeeding it, and the car-track capacity of each station; substantially as herein described. 125

2. The combination, in a railway guide-book, of an underlapping fly-index on each right-hand page, each of which fly-indices, ex- 130

cepting the first, has printed thereon the names of two more stations than the fly of the page next preceding it, the scheduled number of two oppositely-running trains printed on the underlapping bottom of each fly, a column of figures on the left-hand page indicating, where opposite the stations, the time of the arrival or departure of said trains, and a column of figures on the right-hand page, where such figures are opposite the names of the sta-

tions, designating the time of the arrival or departure of the other of said scheduled trains, as herein described.

Signed at Troy, New York, this 18th day of February, 1884, and in the presence of the two ¹⁵ witnesses whose names are hereto written.

SAMUEL FREDERICK STEVENS.
